[57] CLAIM

The ornamental design for a control console, as shown and described.

DESCRIPTION

FIG. 1 is a perspective view of the control console showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a back elevational view thereof;

FIG. 7 is a bottom plan view thereof; and

FIG. 8 is a perspective view thereof.

The broken line disclosure shown in FIG. 8 is for illustrative purposes only and forms no part of the claimed design.

FIG. 1

FIG. 2.

FIG. 3.

FIG. 4.

FIG. 5.

FIG. 6.**FIG. 7.**
